UNITED STATES PATENT OFFICE.

ALFRED M. ZIEGLER, OF NEWTON, MASSACHUSETTS.

GARMENT SUPPORTER.

Application filed December 14, 1921. Serial No. 522,258.

To all whom it may concern:

Be it known that I, ALFRED M. ZIEGLER, a citizen of the United States, and a resident of Newton, county of Middlesex, and State 5 of Massachusetts, have invented an Improvement in Garment Supporters, of which the following description, in connection with the accompanying drawings, is a specification, like characters on the drawings representing like parts.

This invention relates to garment supporters and the object is to provide a construction applicable to various devices of this class and to analogous devices which will be 15 of superior neatness, efficiency and durability.

My invention will best be understood by reference to the following description of the specific embodiment thereof shown by way 20 of example in the accompanying drawings wherein for purposes of illustration I have illustrated the invention as embodied in a pair of suspenders and wherein:

Fig. 1 is an elevation of a portion of the 25 shoulder strap and the end piece of a pair of suspenders;

Fig. 2 is a partial vertical section on an enlarged scale through one of the extremities of the end; and

Fig. 3 is a section on the line 3—3 of 30 Fig. 2 on a still larger scale.

In the form of the invention shown the improvements illustrative of my invention are embodied in the so-called end 5 of the 35 suspenders which I have shown secured by a suitable fitting embodying the loop 7 to the shoulder strap 9. The suspenders here illustrated are of the elastic end type in which the resiliency is obtained through the 40 ends and herein the body portion 11 of the end embodies in its construction (see Fig. 2) a suitable rubber spring in the form of a round cord-like body of rubber 13. This core 13 is surrounded by a braided covering 45 of textile material 15. At the middle of the end in the zone $a-a$ (Fig. 1) the braiding is preferably applied at a relatively shallow pitch so as to compress the rubber 13 and bind it into a comparatively inex- 50 tensible firm body of small size adapted to be embraced and engaged by the supporting loop 7. In the zones $a-b$ at either side of the central zone the pitch of the braiding is gradually increased and here the rubber is 55 under comparatively little restraint providing freely extensible and resilient portions.

At the points b , however, immediately adjacent the terminals the pitch of the braiding is preferably sharply decreased so that the extreme end of the rubber core 13 is 60 compressed and bound together to provide the reduced terminal portion 17 best seen in Fig. 2 for purposes which will herein-after be more readily understood.

In a garment supporter utilizing a round 65 element, whether resilient as here or otherwise, inconveniences arise when it is attempted to secure the element to adjacent parts. This is particularly true in a suspender end. Customarily the cord is looped 70 to form a button receiving loop and secured by a metal clamp. Passing over the disadvantages attending the use of metal, this construction is open to objection since there is a tendency for the button hole to swivel 75 around the button when the suspenders are thrown off the shoulders, for instance, and the end thus becomes twisted. In accordance with my present invention I utilize flat buttonhole members, conveniently formed of 80 sections of webbing, which are suitably attached to the round portion of the suspender end and which have no tendency to twist or turn about the button.

The buttonhole loops 19 are conveniently 85 formed from a section of textile webbing and the upper portions thereof are folded about the reduced terminals 17 and substantially fill out the reduced portion providing a smooth and pleasing uniformity where the 90 round cord merges into the buttonhole loops. The loops 19 are secured to the braided covering 15 which surrounds the loop and this is preferably effected by means of stitches 21 passing through the folded 95 portion of the loop 19 and the covering 15 as best shown in Fig. 3 at the sides of the core 13. While this stitching may be effected in various ways I preferably use an over and over stitch encircling the core 13 100 and adapted to overlie the edges of the folded portion of the loop 19 so as to hold these down.

As shown by Fig. 1 the stitching is prefer- 105 ably of some extent longitudinally and it serves to bind together the elements which form the braiding and hold them against relative shifting so that there is little or no tendency for them to fray out. The com- 110 pression of the rubber core 13 by the braid- ing at the reduced end 17 provides a firm support and resistance for the attachment

of the button loop 19 and the stitches preferably are also bound about this reduced end and the button loop is, as it were, seized to the end of the rubber spring, this 5 providing in itself an attachment of some strength. However, the loop is intimately secured to the braided threads of the covering 15 and under tension the strain is transmitted to these threads which constrict about the core and the strain on the button-hole loop is carried not at a single point but throughout the entire length of the resilient end portion of the suspender.

In the example shown the use of metal 15 fastenings is entirely avoided. The elimination of metal from the exterior portions of the supporter is not only desirable in itself but the avoidance of the proximity of metal to the rubber spring 13 is further desirable.

While I have herein described in detail the invention as applied to the end of a pair of suspenders and while it presents certain advantages for such a use specifically, some 25 of which have been pointed out, it will be clear of those skilled in the art that the invention is by no means limited to use on a suspender end and it is applicable to various uses in which it is desired to make a connection to a rubber spring more particularly when the element to be connected is of flat flexible material, such as webbing or the like, and that it also finds application in cases where such a flat member is to be secured to another member of round or cord-like form. The invention is therefore not to be understood as limited in its broader aspects to use on a suspender but the principles exemplified by the construction shown 35 in the drawings and which I claim as new and desire to secure by Letters Patent I shall express in the following claims.

Claims:

1. In an article of the class described an 45 element of flat flexible strip, a rubber spring and a braided covering encircling the spring, said element being secured to the covering and suspended in strain-transmitting relation therefrom by stitching passing through the covering at separated points around the end of the spring.

2. In an article of the class described an 50 element of flat flexible strip, a rubber spring and a braided covering encircling the

spring, said element being secured to the 55 covering and suspended in strain-transmitting relation therefrom by stitches encircling the end of the spring.

3. In an article of the class described a 60 rubber spring, a braided covering thereover, said covering constricting the end of the spring to provide a reduced end therefor an element of flat flexible strip folded about said end and suspended in strain-transmitting relation from said covering by stitches 65 passing through the covering at separated points around the end of the spring.

4. In an article of the class described a 70 rubber spring, a braided covering thereover, said covering constricting the end of the 75 spring to provide a reduced end therefor an element of flat flexible strip folded about said end and suspended in strain-transmitting relation from said covering by stitches encircling and tensioned about said reduced end.

5. In an article of the class described, a 80 rubber spring, a braided cover thereover, an element of flat flexible material folded about the end of the spring and suspended 85 in strain-transmitting relation therefrom by stitches encircling the end of the spring and binding down the edges of said folded element.

6. In an article of the class described a 85 rubber spring, a covering braided thereover the pitch of the braiding being sharply decreased at the end of the spring and providing a reduced and compressed end presenting an abrupt shoulder, an element of flat web folded around the end and fitted to the shoulder and stitching suspending said web in strain-transmitting relation from said covering.

7. In an article of the class described an 90 elongated cylindrical body and an associated element of flat flexible material having the end portion thereof folded about the end of the body and secured by stitches passing through the sides of the body and embracing the central portion thereof.

8. A structure as defined in claim 7 95 wherein the stitches overlie the edges of the flexible material to hold the same in its folded position about the body.

In testimony whereof, I have signed my name to this specification.

ALFRED M. ZIEGLER.
